(57) **CLAIM**

The ornamental design for a side press mop wringer, as shown and described.

DESCRIPTION

FIG. 1 is a top frontal perspective view of a first embodiment of a side press mop wringer according to my new design; FIG. 2 is a front view of the side press mop wringer shown in FIG. 1;

FIG. 3 is a back view of the side press mop wringer shown in FIG. 1;

FIG. 4 is a left side view of the side press mop wringer shown in FIG. 1;

FIG. 5 is a right side view of the side press mop wringer shown in FIG. 1;

FIG. 6 is a top view of the side press mop wringer shown in FIG. 1; and,

FIG. 7 is a bottom view of the side press mop wringer shown in FIG. 1.

The ornamental design that is claimed is shown in solid lines in the drawings. The broken lines in the drawings are for illustrative purposes only and form no part of the claimed design.
